ADJUSTABLE CARPENTER'S SQUARE
Permil N. Nelson, Galesburg, Ill., assignor to
Lynn H. Ewing, Rock Island, Ill.
Filed May 28, 1962, Ser. No. 198,374
1 Claim. (Cl. 33—93)

My invention relates to a new and useful improvement in an adjustable carpenter's square and more particularly to a carpenter's right angle square which is capable of being adjusted through a 90° arc to properly prescribed, pre-selected angles.

A principal object of my invention is in the provision in a device of this character of means for angularly adjusting a movable element of a carpenter's square relative to the fixed right angularly disposed legs thereof for defining with a great degree of accuracy pre-determined angles therebetween.

A further object of my invention is in the provision in a device of this character of a means for releasably locking the movable angle-defining element in any pre-selected position between the fixed right angularly disposed legs of the carpenter's square.

Yet another and equally important object of my invention is in the provision in a device of this character of a means for readily determining the angle described by the movable element of my adjustable carpenter's square.

Other objects will appear hereinafter.

The invention consists in the novel combination and arrangement of parts to be hereinafter described and claimed.

The invention will be best understood by reference to the accompanying drawings showing the preferred form of construction, and in which:

FIG. 1 is a plan view of my adjustable carpenter's square in its normal or collapsed condition.

FIG. 2 is a rear plan view similar to FIG. 1.

FIG. 3 is a plan view of my improved carpenter's square in an adjusted or angle-defining position.

FIG. 4 is a rear view similar to FIG. 3, and

FIG. 5 is a perspective view of my improved carpenter's square showing in an adjusted angle-defining position the movable element thereof.

My adjustable carpenter's square includes a base leg 10 which is formed in an inverted L-shape in cross section thus providing a depending base flange 11, and a supporting flange 12. Extending at right angles to the base leg 10 is a reversed L-shaped perpendicular leg 13. This perpendicular leg 13 provides a bottom flange 14 and a vertical extending guide flange 15. The bottom 50 flange 14 of the perpendicular leg 13 is fixedly attached to the supporting flange 12 at the vertex 16 of the right angle that is defined between the base leg 10 and the perpendicular leg 13.

Pivots attached at the vertex 16 is a movable angle 55 arm 17. This angle arm 17 is formed to correspond to the base leg 10 and as such defines an inverted L-shape member in cross section. The angle arm 17 provides a base member 18 which extends in the same plane as the depending base flange 11 of the base leg 10. The angle 60 arm 17 provides a support member 19 formed to extend in the same horizontal plane as the support flange 12 of the base leg 10. By this construction and arrangement of parts, the angle arm 17 may be seated in facial abut-

2

ment with the underside surface of the base flange 11 and support flange 12 of the base leg 10 when in a collapsed condition as viewed in FIGS. 1 and 2.

The free end 20 of the angle arm 17 is movable through an arc between the base leg 10 and the perpendicular leg 13 and as such is capable of bisecting the right angle formed between legs 10 and 13, so as to define any angle therebetween. A positioning rod 21 has one end pivotally connected as at 22 to the underside of the support member 19 of the angle arm 17 intermediate the extremities thereof.

The opposite end of the positioning rod 21 carries a threaded stud 23 which is adapted to extend through an elongated slot 24 formed in the bottom flange 14 of the perpendicular leg 13. A wing nut 25 is adapted to be threaded upon the stud 23 so as to releasably latch the same in any position throughout the length of the slot 24.

A triangularly shaped plate 26 is positioned between the base leg 10 and perpendicular leg 13 adjacent the vertex 14 thereof. This plate 26 has its hypotenuse scored as at 27 to indicate the different angles that may be prescribed through the right angle formed by the base leg 10 and perpendicular leg 13.

Referring to FIG. 3 I show my carpenter's square adjusted to define an approximate 40° angle between the base element 18 of the angle arm 17 and the guide flange 15 of the perpendicular leg 13. The threaded stud 23 has moved upwardly through the slot 24 and the wing nut 25 has been threaded thereon into engagement with the bottom flange 14 so as to latch the angle arm 17 in this selected angled position.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

An adjustable carpenter's square comprising

- (a) a base leg angularly disposed with respect to a perpendicular leg,
- (b) said base leg providing along one edge an elongated flange depending therefrom and adapted to engage an edge of a work piece so as to position said perpendicular leg at right angles thereto,
- (c) an angle arm pivotally connected to the vertex of the angularly disposed base leg and perpendicular leg and having a collapsed position and an extended position where it is angularly positioned between said base leg and perpendicular leg to describe a pre-selected angle therebetween,
- (d) said angle arm providing along one edge thereof an elongated lateral flange extending in a plane perpendicular to said base leg and adapted for nesting relation with respect to the lateral flange of said base leg when said arm is in its collapsed position and for engaging the edge of a work piece so as to angularly position said perpendicular leg relative thereto when it is moved angularly between said base and said perpendicular leg,

- (e) a positioning arm pivotally connected at one end to said angle arm and slidably connected to said perpendicular leg for positioning said angle arm in a pre-selected angled position relative to said base leg and said perpendicular leg, and
 (f) means for latching said positioning arm to said perpendicular leg in a selected position for releasably latching said angle arm in a preselected angle position.
